UNITED STATES PATENT OFFICE.

FREDERIC C. BILLINGS, OF HARTFORD, CONNECTICUT, ASSIGNOR TO THE BILLINGS & SPENCER COMPANY, OF CONNECTICUT.

DESIGN FOR A DIE-SHOE.

SPECIFICATION forming part of Design No. 28,102, dated December 28, 1897.

Application filed November 2, 1897. Serial No. 657,222. Term of patent 7 years.

To all whom it may concern:

Be it known that I, FREDERIC C. BILLINGS, a citizen of the United States, residing at Hartford, in the county of Hartford and State of Connecticut, have invented and produced a new and original Design for a Die-Shoe, of which the following is a full, clear, and exact specification.

Figure 1 of the accompanying drawings is a plan or top view of a die-shoe embodying my present design, while Fig. 2 is a side view thereof projected from Fig. 1. Fig. 3 is an end view of the die-shoe of Figs. 1 and 2 projected from the latter figure. Fig. 4 is an end view in section taken on the line 4-4 of Fig. 1, showing the inner side of the upper end of the die-shoe of the latter figure.

Similar characters designate like parts in all of the figures of the drawings.

The leading characteristics of this design are best apparent in Figs. 1 and 4, and com-

prise a die-shoe having a sunken central panel or depression 6, bounded upon its longitudinal sides by the raised margins 7 and 8 and bounded upon its ends by the raised bosses 9 and 10. These bosses are raised somewhat above the side margins 7 and 8, with one of which they are preferably integral. 25

The design herein shown and described is especially intended for die-shoes to be used 30 in connection with drop-hammers and similar machinery and forms a graceful member which harmonizes with the prevailing style and patterns of such machines.

I claim—

The design for a die-shoe herein shown and described. 35

FREDERIC C. BILLINGS.
